UNITED STATES PATENT OFFICE

2,315,017

SEPARATOR FOR LIQUIDS HAVING
DIFFERENT SPECIFIC GRAVITIES

Herbert Alexander Thompson, Benton, England

Application October 11, 1938, Serial No. 234,452
In Great Britain February 24, 1938

5 Claims. (Cl. 210—54)

This invention relates to float-actuated means for controlling the discharge of collected separated liquid from a separating device for separating liquids of different specific gravities from a mixture of such liquids which does not tend to form a true miscible solution.

In the specification of my earlier U. S. Patent No. 2,036,730 I have described a separator provided with float controlled means for effecting the automatic discharge of one of the separated liquids when a predetermined amount of the liquid has collected and the control float is counterweighted by a movable balance weight which is adjustable in position to provide correct operating conditions when the specific gravities of the separated liquids vary, as in some industrial processes.

The present invention is an improvement in the control device referred to in my abovementioned patent and one object of the present invention is to provide an improved arrangement in which the necessity for the shiftable balance weight is avoided and a further object is to provide a simple and satisfactory control device which is self-adjusting for variations in the specific gravities of the liquids passing through the separator and therefore does not require the attention of an attendant.

In the present arrangement, as in the construction described in the abovementioned U. S. A. patent specification, the discharge of the recovered liquid which collects, as it is separated from the mixture, in a collecting dome or chamber is controlled by the movements of a lever actuated by a float moving up and down with the level of the collected liquid (i. e. the line of separation between the collected liquid and the mixture). In the arrangement according to the present invention a main float and a pilot float are carried at opposite ends of the lever (or of a lever system) and are arranged so that the pilot float, which is always wholly immersed in the flow liquid passing through the apparatus, has normally a greater effective action than the main float. Thus, before the recovered liquid starts to collect (and both floats are consequently immersed in the same liquid) the action of the pilot float overcomes that of the main float but as the latter becomes immersed in the separated liquid collected in the dome the change in weight of the main float (due to the different specific gravity of the liquid in which it is now immersed) causes the action of the main float to overcome that of the pilot float with the result that the lever on which the floats are

carried is ultimately tilted on its fulcrum to cause the opening of a discharge valve for the collected liquid. Both the main float and the pilot floats as described herein are made of the same size and weight so that they normally have the same displacement but when the recovered liquid is lighter than the flow liquid of the mixture from which it is separated the pilot float is additionally weighted so that when both floats 10 are immersed in a common liquid (as is the case when no separated liquid has yet started to collect) the pilot float acts to raise the main float to the top of the collecting dome but as the lighter liquid (e. g. oil) collects the weight loss 15 of the main float (due to its immersion in a liquid) becomes less owing to the lighter specific gravity of the oil and this change of immersion increases the operative weight of the main float and thereby overcomes the additional or bias weight added to the pilot float and the main float follows the level of oil down and tilts the lever on its fulcrum to cause discharge of the oil when a predetermined amount has collected.

As the oil is discharged the heavier liquid of 25 the mixture flows in to take its place and the pilot float is again able to overcome the effect of the main float and return the lever to its original position.

If the recovered liquid is heavier than the 30 mixture from which it separates the apparatus is used in an inverted position and the main float is made heavier than the pilot float and the main float decreases in weight as it becomes immersed in the recovered heavier liquid and is 35 able to follow up the rising level of recovered liquid until discharge of the collected liquid occurs from the inverted dome or sump.

It will be understood that the pilot float can be 40 made smaller than the main float providing that the leverage distance from the fulcrum to the pilot-float is correspondingly increased to give an equivalent power factor equal to a float of the same size as the main float when equal leverages are used. Alternatively a pilot float smaller 45 than the main float can be employed with either equal or unequal leverages for the two floats if the size to weight ratio of the pilot float is suitably altered in comparison with that of the main float.

50 The arrangement according to the present invention will best be understood from the following description with reference to the accompanying drawings, in which:

Fig. 1 is a diagrammatic representation of a 55 separator with the collecting dome shown in sec-

tion, and showing the positions of the floats before any lighter separated liquid has collected within the collecting dome.

Fig. 2 is a fragmentary view of the top portion of Fig. 1 but showing the positions of the floats just before the collected liquid in the dome commences to discharge.

Figs. 3 and 4 are views corresponding to Figs. 1 and 2 but showing the floats on a lever system instead of on a single lever.

Fig. 5 is a part sectional view of a modified form of separator and,

Figs. 6 and 7 are sectional elevations showing other modifications.

The separator is shown as suitable for cases in which the recovered liquid (assumed to be a light oil) is of lighter specific gravity than the flow-liquid from which it separates.

In Figs. 1 to 5 the body of the separator is indicated at 1 and has a collecting dome 2 in which the lighter separated liquid (i. e. the oil) collects and to which the separated oil is led by upcast pipes 3. The separator has inlet and outlet pipes 4 and 5 and the oil dome 2 has a water-exchange pipe 6 through which the liquid displaced from the oil dome 2 as the oil collects therein passes back into the body of the separator. These parts 1 to 6 correspond with the parts, 1, 8, 19 and 26, 9, 10 and 36 respectively of the construction described in U. S. Specification No. 2,036,730. The oil which collects in the dome 2 is discharged therefrom, when a predetermined amount has collected, through pipe 7 which is provided with a discharge valve 8 operated by fluid under pressure supplied to the operating cylinder 9. The supply of pressure fluid to the cylinder 9 is controlled by a rotary or shuttle valve actuated by the movements of the lever 10 in the manner described in Specification 2,036,730 and the lever 10 is float-operated in the manner hereinafter described. The parts 7 to 10 correspond with the parts 37, 38, 39 and 43 respectively in the construction described in Specification 2,036,730.

In Figs. 1 and 2 of the present case a single lever 10 is shown which is fulcrumed on a shaft 11 suitably supported in shaft bearings to reduce friction to the lowest possible degree. At opposite ends of the lever 10 and at equal leverage distances from the fulcrum 11 are attached a main float 12 (corresponding to float 42 in the prior patent) and a pilot float 13. The amount of oil which is allowed to collect before discharge occurs is indicated by the distance A and the lever 10 is pivoted just below the level B (Fig. 2) which indicates the plane of separation between the collected liquid and the mixture when discharge commences. Suitable stops (not shown) are provided for the lever 10 to limit the upward travel of the main float 12 and other stops are provided to limit the downward movement to a position in which the lever 10 is horizontal.

The main float 12 is attached to the upper side of the lever 10 whilst the pilot float 13 is attached to the underside of the lever so that in the horizontal position of the lever as shown in Fig. 2 the main float 12 is above the maximum oil level line B and the pilot float 13 is below it so that the latter always remains immersed in the heavier liquid flowing through the separator and cannot enter the recovered oil space.

The main float 12 and the pilot float 13 are first constructed to exactly the same volumes and weights so that thus far they are the equivalent of each other, and both heavier than the heaviest flow liquid that they may be immersed in. The

5 pilot float 13 is then loaded by weights such as lead shot, iron borings, cement, sand or other suitable loading material, in order to give it a bias over the main float 12 whereby the latter is partially counterpoised so that it tends to rise in the heavier of two liquids of slightly different specific gravities but tends to sink in the lighter of the two liquids, which may be, for instance, fresh water of specific gravity 1 and oil of .99 specific gravity.

10 As the two floats were originally constructed to the same weight and volume and their weights were heavier than the same volume of the heaviest flow liquid to be used, it will be evident that prior to the bias loading of the pilot float neither would have any operative effect over the other when immersed in the heaviest flow liquids, as each is heavier than the liquid and each would actually have a sinkage effort in the same, equal and opposite to each other.

15 If the apparatus is now filled with fresh water of say 1.0 specific gravity, it will be evident that both floats will each lose the same amount of weight due to immersion in the same liquid, as any body which is immersed in a liquid loses 20 weight by exactly its volume weight of the liquid it displaces.

25 As at first constructed each float was to be made heavier than the same volume of the heaviest flow-water it will be evident that on immersion only this excess weight would remain on each as effective sinking effort and that being so their excess weights would be the same on each side of the fulcrum 11 and they would be merely 30 in a state of equipoise.

35 However, as the pilot float 13 has been given in addition a bias loading over the main float 12, it will be evident under such loading that immersion in say fresh water will result in the main 40 float 12 becoming buoyant, whilst the pilot float 13 will sink on account of its bias weight, thus overcoming the position of equipoise which would otherwise occur if the floats were of similar weight, as well as equal volumes.

45 This means that in fresh water the main float will have a definite buoyant effort, which operates through the fulcrum shaft 11 of the lever 10 to cause the oil-discharge valve 8 to be closed. The floats 12 and 13 and lever 10 then have the 50 position shown in Fig. 1.

55 If it is now assumed that oil has been recovered from the flow-water passing through the separator, then this oil will be passed up to the top of the oil dome 2 through pipes 3 and an equivalent volume of water will pass out from the dome 2 through pipe 6 back into the flow through the separator.

60 As this oil accumulates downwards in dome 2 it will cover the main float 12 and as this has only been counterpoised to float in water but not in a lighter liquid, the main float is not buoyant in this oil and must therefore sink, i. e.: follow the oil-water level downwards in the dome 2.

65 The pilot float does not prevent this because as the oil is lighter than the fresh water it cannot support the same amount of the constructed weight of the float as the fresh water did, and the main float therefore appears to gain in weight relative to the pilot float, whereas the pilot float 70 still remains immersed in fresh water and its apparent loss in weight due to immersion is unchanged. On this account the arrangement results in the bias being changed over to the main float without any shift of balance weights, as due to oil immersion its excess weight is now heavier

than that exerted by the pilot float which is still in the fresh water.

This means that the main float 12 has now a definite sinking effort in the oil and so gradually falls as the oil accumulates and when the floats and lever reach the position shown in Fig. 2 in which the lever 10 becomes horizontal the shuttle-valve will be reversed, causing the oil discharge valve 8 to be opened to allow the accumulated oil to be discharged automatically from the oil dome 2.

As the oil is discharged the main float 12 again becomes buoyant in the heavier liquid and will follow the oil-water level upwards, because the equivalent amount of flow-water will re-enter the dome by pipe 6, and when the main float reaches its top position again, the oil discharge valve will be automatically closed and the accumulation of oil will commence afresh.

Now supposing the oil-contaminated water flowing through the separator changes to a water of heavier specific gravity, say salt water, and both floats as balanced for fresh water, are immersed therein, it will be found that the main float is still buoyant in the same manner as in the fresh water because both floats having the same volumes will each lose their "volume-weight" of salt water, but the pilot float will still have its bias loading in addition.

This means that in any flow-liquids the two floats gain or lose equal "volume-weights" in every case, so that any apparent changes in weight due to immersion in changed flow liquids are automatically cancelled or balanced out as between the two floats and the counterpoise bias given by the pilot float due to its additional loading is maintained.

When the oil separated from the salt water accumulates in the oil dome 2 the main float gains an increase in weight as before and thereby increases its "excess weight." As the pilot float still remains in the salt water its "excess weight" cannot increase and therefore (as in the case of the fresh water flow), the bias is transferred to the main float without any shift of balance weight and the main float will be heavier than the pilot float and so sink with the oil-water level and ultimately cause the oil discharge valve 8 to be opened to discharge the oil.

In Figs. 3 and 4 there is shown an arrangement similar to that shown in Figs. 1 and 2 except that the lever carrying the floats 12 and 13 is in two parts 10' and 10'' fulcrumed at 11' and 11'' and connected by a link 14. This arrangement operates in the same way as that described with reference to Figs. 1 and 2 and enables longer leverages to be obtained without the necessity of having the oil dome 2 made larger. In Fig. 3 the parts are shown in the positions taken up prior to the accumulation of oil in the dome 2 while Fig. 4 shows their positions just prior to discharge of the collected oil. It is obvious that other forms of multiple levers can be employed.

Fig. 5 shows an arrangement similar to the construction shown in Figs. 3 and 4 except that the oil dome 2 is partially housed within the body 1 of the separator in order to reduce the total height of the complete apparatus. In this figure the final positions of the floats 12 and 13 just prior to discharge of the recovered oil is shown in dotted outlines.

Fig. 6 shows a construction in which a single lever 10 is used to carry the floats 12 and 13 as in Figs. 1 and 2 but in this case the oil dome 2 and the oil upcast channel 3 are incorporated in

the body of the separator. The lever 10, pivoted at 11, is housed partly in the oil dome 2 and partly in the rest of the separator to give increased leverage while economising in the size and construction of the complete apparatus. This figure also shows the shuttle valve 15 which is actuated by the lever 10 and controls the supply and discharge of pressure fluid to and from the cylinder 9 through pipes indicated at 16.

Fig. 7 shows a similar arrangement to Fig. 6 but in this case the oil collecting chamber 2 occupies the whole top part of the separator and the pilot float 13 also carries an extension 17 forming a valve controlling the outlet of flow water from the separator. Instead of being attached directly to the ends of the lever 10 the floats are carried on extensions 18 and 19 pivoted to the ends of the lever so that the floats can travel in vertical instead of radial paths. Reference 20 indicates an air or gas vent pipe leading to the atmosphere.

In all the constructions illustrated in Figs. 4 to 7 the operation is the same as that described with reference to Figs. 1 and 2.

The above described self-balancing automatic gear enables all forms of hand control or setting of the specific gravity gear to be dispensed with in the employment of the apparatus, as the twin floats enable the plant to deal with fresh or salt water at any temperature as main flow through the separator, and at the same time discharge oil of any kind that has a lighter specific gravity than the flow-water. On this account the plant is especially suitable for dealing with oily-condensate water from steam-engines or heating coils, as the apparatus is self-correcting for specific gravity changes occurring in the condensate either from cold to hot or vice-versa.

The apparatus may be however employed for any purpose wherever two or more non-mixable liquids have to be separated and discharged, particularly where the flow-liquid is liable to change in specific-gravity or have its specific gravity altered due to heating or cooling, as it is self-correcting where changes occur in the specific gravities of the liquids.

The same apparatus in an inverted form can be utilised for discharging oils that are heavier than the flow-water, by employing it in conjunction with the inverted separator shown in Fig. 7 of Specification No. 2,036,730, but in this inverted position of course the main float is made heavier than the pilot float and has an apparent loss in weight as it becomes immersed in the heavier oil instead of in the flow water, so that in such cases it is an upward flotation effort which is transferred from the pilot float to the main float. Apart from this the operation is the same as that described for oils lighter than the flow liquid from which they are separated.

What I claim as my invention and desire to secure by Letters Patent is:

1. Apparatus for the separation of liquids of different specific gravities from a mixture of such liquids comprising a closed receptacle, in which the mixture separates into a lighter upper liquid and a lower heavier liquid, said receptacle having an inlet for the mixture of liquids, a lower outlet for the heavier liquid, an upper outlet for the lighter liquid, means including a valve controlling the flow of the lighter liquid through said upper outlet, power means operated by fluid under pressure for actuating said valve, means to supply a fluid under pressure to said power means, a

second valve normally closed controlling said last mentioned means, a valve operating means comprising a pilot float, a main float, at least one lever connecting the floats, a fulcrum for said lever, said floats being of exactly equal volumes, said main float being above and said pilot float below the lever, and means connecting said valve operating means and said lever, said lever and floats being so constructed and arranged that the pilot float rises above its normal level when the main float is immersed in the lighter liquid, thereby actuating said second valve to admit a fluid under pressure to said power means to open said upper outlet valve.

2. In an apparatus as claimed in claim 1, a chamber in open communication with said receptacle in which the lighter liquid collects and in which said floats and connected lever are located, said chamber having therein a predetermined plane of maximum separation between the lighter and heavier liquids, said fulcrum of said lever being located below said plane of maximum separation.

3. An apparatus as claimed in claim 1, further characterized by said fulcrum of said lever located below the plane of selected maximum separation of the lighter and heavier liquids, said main float lying above the lever, said pilot float lying below the lever.

4. An apparatus as claimed in claim 1, further characterized by the fact that the pilot and main floats are connected to the lever at different horizontal levels with the main float uppermost and adapted to float in the mixture of liquids and sink in the lighter separated liquid, and means to prevent the pilot float from rising above the selected line of separation between the liquids.

15 5. An apparatus as claimed in claim 1, further characterized by the fact that said pilot float is weight biased with respect to the main float to normally sink in the liquid mixture with an accompanying rise of the main float in the mixture, said main float constructed and arranged as to weight to sink in the lighter separated liquid.

HERBERT ALEXANDER THOMPSON.
